UNITED STATES PATENT OFFICE.

NATHANIEL E. SMITH, OF JERSEY CITY, NEW JERSEY, ASSIGNOR OF ONE-HALF TO JOHN R. MCPHERSON, OF SAME PLACE.

CAR-COUPING.

SPECIFICATION forming part of Letters Patent No. 443,466, dated December 23, 1890.

Application filed April 21, 1890. Serial No. 348,936. (No model.)

To all whom it may concern:

Be it known that I, NATHANIEL E. SMITH, a citizen of the United States, residing at Jersey City, in the county of Hudson and State of New Jersey, have invented certain new and useful Improvements in Car-Coupling Attachments; and I do hereby declare the following to be a full, clear, and exact description of the invention, such as will enable others skilled in the art to which it appertains to make and use the same.

This invention relates to car-couplings.

Heretofore great difficulty has been experienced in the use of car-couplings because of the difference in height of the draw-heads of adjacent cars to be coupled. The main cause of this difficulty, especially in freight-cars, is the inequality in the weights of the loads of the cars, resulting in the unequal depression of the springs of the cars and consequently in the unequal height of the body of the cars and the draw-heads and couplers, which are attached to the bodies of the cars.

The object of the present invention is to produce an attachment for car-couplings whereby the coupler-heads shall automatically be kept at the same height irrespective of the load on the cars. Furthermore, the object is to produce an attachment for car-couplings so constructed and arranged that the coupler-heads shall automatically be kept at the same height, and which shall be capable of being regulated in height by hand independent of the automatic means for determining its position.

With these objects in view the invention consists, essentially, in an attachment for car-couplings in which the coupler-heads have a limited up-and-down movement, consisting in a lever bearing upon or attached to the coupler-head, the lever being attached to the body of the car by a vertically-adjustable connection and attached to or supported upon one or more of the axles of the car independent of the body of the car.

Furthermore, the invention consists in an attachment for car-couplings in which the coupler-head is capable of a limited up-and-down movement, comprising a lever connected to or bearing upon the coupler-head ful-

crumed on one of the axles of the car or on a part connected therewith, and connected to the body of the car by a bar or rod capable of up-and-down movement, and means connected with the bar or rod for effecting the up-and-down movement of the bar or rod, consisting in a rack on the bar or rod meshing with a pinion mounted on the body of the car and connected with a crank for imparting a rotary movement to the pinion, whereby the coupler-head may be raised or lowered by hand.

I have illustrated the invention in the accompanying drawings, in which—

Figure 1 is a central longitudinal section of one end of a car, showing a coupler-head and my novel attachment arranged in proper operative relation thereto. Fig. 2 is a plan view of an ordinary freight-car having my invention applied thereto, the platform or floor being removed in order more clearly to illustrate the invention. Fig. 3 is an end view of a car having my invention applied thereto. Fig. 4 is a perspective view of a frame or bar to be attached to the axle and designed to act as a support for the lever, and Fig. 5 is a view of a modified form of support for the lever.

In the drawings, A represents one of the axles of the car provided with the usual wheels and boxes a. Attached to these boxes by bolts or the like is a frame B, having near each end bends b to provide for the reception of the wheels a² of the cars when the frame is in position with its ends b² bolted to the boxes a of the axle. The central portion b³ of the frame B is curved, the curve corresponding to a circle drawn with the bolt, upon which the truck of the car is swiveled as a center. This portion b³ is slotted at b⁴, and in this slot is mounted a block C by means of a retaining-bolt c. In this block C is pivoted a lever D, the forward end D² of which extends up into the housing of the coupler-head and bears against the coupler-head. The rear end D² of the lever is connected by a suitable bar or rod d³ to the body of the car. The preferred manner of attaching the bar or rod d³ to the body of the car is by forming the upper portion of the bar or rod d³ with a

rack, with which meshes a pinion d^4 , attached to the end of a shaft d^5 , which may be provided with a handle for imparting a rotary motion thereto, or which may be connected 5 with a shaft d^6 , extending from the end of the car and connected with the shaft d^5 by suitable gears.

It is not essential to the operation of the device that the hanger be attached to the 10 body of the car in this way, but it is of advantage, as it permits of the adjustment of the height of the coupler-head by hand independently of the automatic means of adjustment when this is desirable on account of 15 the construction of the cars.

I do not wish to limit myself to the particular means shown of mounting the lever upon the axle or upon a part connected therewith, as it is obvious that various means may be 20 employed for accomplishing this. For instance, the shaft may be provided with a collar E , as shown in Fig. 5 of the drawings, this collar being mounted upon the center of the axle free to turn thereon and provided with 25 a swiveled notched block e , in which the lever D may be mounted.

The operation of the attachment, as herein shown, the lever being arranged in suitable position, with its forward end bearing against 30 the coupler-head, is, when sufficient load is imposed upon the body of the car, to depress its supporting-springs and lower the rear end of the lever, and as this lever is mounted upon the axle of the car or upon a part connected therewith independent of the body of the car the effect will be to raise the forward end of the lever (that end bearing against the coupler-head) and raise the latter a distance corresponding to the distance which 35 40 the rear end of the lever is depressed. Thus it will be seen that by my device I effect the

automatic retention of the coupler-head at a predetermined height irrespective of the load imposed upon the car. If by any means the attachment should become deranged, the adjustment of the height of the coupling may be accomplished through the gears and rods connected with the bar or rod, by which the lever is attached to the body of the car. 45

Having thus fully described my invention, 50 what I claim as new, and desire to secure by Letters Patent, is—

1. An attachment for car-couplings in which the coupler-heads are capable of a limited up-and-down movement, consisting in a lever 55 bearing upon or attached to the coupler-head connected to the body of the car by a vertically-adjustable connection, whereby the device may be adapted to retain the coupler-head at any desired height, the lever being 60 attached to or supported upon one or more of the axles of the car independent of the body of the car, substantially as described.

2. An attachment for car-couplers in which the draw-head is capable of an up-and-down 65 movement, consisting in a lever connected to or bearing upon the coupler-head fulerumed on one of the axles of the car or on a part connected therewith, and connected to the body of the car by a bar or rod capable of up- 70 and-down movement, and means for effecting the up-and-down movement of the bar or rod, consisting of a rack on the bar or rod, meshing with a pinion on the body of the car and connected with a crank or the like for imparting rotary movement to the pinion. 75

In testimony whereof I affix my signature in presence of two witnesses.

NATHANIEL E. SMITH.
